Primary Examiner — Brett Miller*Assistant Examiner* — Jessica M Gebhart**CLAIM**

The ornamental design for a vacuum storage lid, as shown and described.

DESCRIPTION

FIG. 1 is a first perspective view of a vacuum storage lid showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of the using state of the vacuum storage lid thereof; and,

FIG. 10 is an enlarged view of the selected portion in FIG. 2.

The broken lines shown in the drawings depict portions of the vacuum storage lid that form no part of the claimed design.
